UNITED STATES PATENT OFFICE.

MARTIN E. HERSHEY, OF HARRISBURG, PENNSYLVANIA.

TRACTION-ENGINE OR ROAD-ROLLER.

SPECIFICATION forming part of Letters Patent No. 444,980, dated January 20, 1891.

Application filed June 30, 1890. Serial No. 357,240. (No model.)

To all whom it may concern:

Be it known that I, MARTIN E. HERSHEY, of Harrisburg, in the county of Dauphin and State of Pennsylvania, have invented certain

5 new and useful Improvements in Traction-Engines or Road-Rollers; and I do hereby declare the following to be a full, clear, and exact description of the same, reference being had to the accompanying drawings, forming 10 a part of this specification, and to the letters of reference marked thereon.

In a prior patent granted to me January 3, 1888, No. 375,815, I described and claimed a novel form of tank and fuel-box arrangement 15 for road-rollers or traction-engines, and the present arrangement is designed as an improvement upon the structure disclosed in said patent, the objects being to provide a machine of the character indicated, in which

20 the tank and fuel-boxes are brought in close to the main axle, thereby leaving the space in rear of the drivers practically clear and unobstructed, enabling the engineer to see exactly which portion of the roadway will be 25 rolled, and at the same time permitting the machine to turn short angles in close proximity to trees, tree-boxes, curbs, or other obstructions without danger of striking the tank or fuel-boxes. The important and very de-

30 sirable feature of leaving a free and unobstructed passage-way for the engineer, as fully set forth in my said patent, being also maintained without sacrificing tank capacity to any material degree.

35 The invention therefore consists in certain novel details of construction and combinations and arrangements of parts, which will be hereinafter more fully described, and pointed out in the claims at the end of the 40 specification.

Referring to the accompanying drawings, Figure 1 is a side elevation of the rear portion of a road-roller constructed in accordance with my invention, the rear wheel being shown in 45 outline only. Fig. 2 is a top plan view, and Fig. 3 is a rear elevation, of the same with the wheels shown in full lines.

Like letters of reference in the several figures indicate the same parts.

50 In the drawings, A indicates the boiler, B the main drive-wheels, and C the main

axle, on which the rear end of the boiler is supported, as shown in my prior patent, or in any preferred manner, as the same forms no part of my present invention. Securely riveted or otherwise suitably attached to the rear end of the boiler or the supporting extensions thereof are the side plates or forward extensions d of the tank D, which latter extends outward beyond the periphery of the drive-wheels, as shown, and in the preferred construction has its lower plate or bottom inclined upward toward the rear, so as to be above any curbstones or low obstructions, and the top or top plate d^2 is made substantially level and is arranged at a convenient height to form the platform upon which the engineer stands to control the machine by means of levers, hand-wheels, &c., mounted on the boiler.

The door for the fire-box in the boiler is of course in the rear end of the same, and to give access thereto the front end of the tank is inclined outward at the top; but the bottom is brought comparatively near the boiler, giving a greater tank capacity without interfering at all with the firing operation or the removal of the ashes, the latter being removed through a suitable door in the front of the ash-pit, as indicated in Fig. 1.

At the rear end of the tank, preferably in rear of the drive-wheels, are located the fuel-boxes E E, projecting some distance beyond the edges of the tank, but not far enough to obstruct the view of the engineer, nor far enough to strike the steel picks in the wheels under any conditions, or trees or other obstructions, in making short turns. To still further increase the effect in this direction, the tanks are made semicircular or semi-cylindrical, as shown. Thus there is no projecting corner to interrupt the view of the engineer or to hit obstructions, as would be the case if the boxes were square.

The tanks E E are preferably supported in place by brackets e e , secured to the sides of the tank and having formed on them supports or bearings f for the scraper-shaft F, which is held in place by a set-screw f' . At the upper rear end of the tank is formed the filling-opening closed by a lid or cover g , which affords a convenient step upon which the en-

- gineer can mount to his place. Below the filling-opening and extending across the rear end of the same is a channel-iron H, in which are formed or to which are attached the coupling-heads I, one at each side of the tank and the other at the center, as will be readily understood. These coupling-heads form a lower step for the engineer, who, it will now be seen, can mount easily to the passage-way between the fuel-boxes and step forward to the position occupied while driving the machine, ample space being left for him to move about and inspect the work being done without leaving his position.
- 15 10 In the bottom of the fuel-boxes I preferably form tool-boxes and provide doors T at each side, opening into the same, and I also form a man-hole K in the side of the tank of any ordinary or preferred construction.
- 15 20 Having thus described my invention, what I claim as new is—
1. In a traction-engine or road-roller, the combination, with the boiler and drive-wheels at the rear end of the same, of the tank located between the drive-wheels and rigidly connected to the rear end of the boiler, leaving a space between the front end of the tank and said boiler, substantially as described.
  2. In a traction-engine or road-roller, the combination, with the boiler, of the tank secured rigidly thereto in rear of the same and having its forward end inclined outwardly at the top, whereby access may be had to the fire-box, substantially as described.
  3. In a traction-engine or road-roller, the combination, with the boiler having rearwardly-extending plates, the main axle passing through said plates, and the drive-wheels, of the tank located between the drive-wheels and secured rigidly to said rearwardly-extending plates, having its bottom or lower

plate inclined upward toward the rear, substantially as described.

4. In a road-roller, the combination, with the boiler and the drive-wheels, of the tank secured rigidly to the boiler and extending outward from between the drive-wheels to form a platform for the engineer, and the semicircular fuel-boxes located at each side of the rear end of the tank above the level of the same and leaving a central passage-way, substantially as described.

5. In a traction-engine or road-roller, the combination, with the boiler, of the tank secured rigidly thereto in rear of the same and extending beyond the drive-wheels, the semicircular fuel-boxes mounted on the tank at the rear end and leaving a central passage-way, the brackets on the tanks for holding said boxes in place, and the filling-orifice, substantially as described.

6. In a road-roller, the combination, with the boiler having the tank secured rigidly thereto in rear of the same to form the engineer's platform, of the channel-iron secured across the rear end of the tank and the coupling-heads on said channel-iron, substantially as described.

7. In a traction-engine or road-roller, the combination, with the boiler, of the tank secured rigidly thereto in rear of the same and extending beyond the drive-wheels, the semicircular fuel-boxes mounted on the tank at the rear on each side, and the tool-boxes formed in the bottom of said fuel-boxes, with the door opening to the exterior, substantially as described.

MARTIN E. HERSHÉY.
